COMBINED TAPE PLAYER, RECORD PLAYER AND HOUSING AMPLIFIER

Yoshiaki Iida, Katano-shi, and Yasuhiko Funabiki, Kobe-shi, Japan, assignors to Matsushita Electric Industrial Co., Ltd., Kadoma-shi, Osaka, Japan

Filed Mar. 20, 1973, Ser. No. 343,887

Claims priority, application Japan Sept. 20, 1972

Term of patent 14 years

Int. Cl. D14—01

U.S. Cl. D56—4 R

FIG. 1

FIG. 2

FIG. 1 is a right side, top and front perspective view of a combined tape player, record player and amplifier, showing our new design; and

FIG. 2 is a right side, top and front perspective view, with a transparent dust cover affixed thereto.

The left side of the combined tape player, record player and housing amplifier is a mirror image of the right side. The rear of the combined tape player, record player and amplifier is plain and unornamented.

Portions of the figures are shaded to indicate contrast and appearance, and portions are diagonally lined to indicate transparency.

The structure which would be visible through the transparent cover of FIG. 2 has been omitted for convenience in illustration.

We claim:

The ornamental design for a combined tape player, record player and housing amplifier, as shown and described.
